RAILWAY TRAFFIC CONTROLLING
APPARATUS

Earl M. Allen, Swissvale, and Henry S. Young, Wilkinsburg, Pa., assignors to The Union Switch & Signal Company, Swissvale, Pa., a corporation of Pennsylvania

Application January 16, 1935, Serial No. 2,076

19 Claims. (Cl. 246—3)

Our invention relates to railway traffic controlling apparatus, and in particular, to approach locking apparatus for preventing the operation of a track switch when a signal governing the movement of traffic over the switch has been cleared, and also for a selected time interval after such signal has been manually restored to stop under certain traffic conditions, so that if an approaching train is unable to stop without over-running the signal, the switch will remain locked, the switch becoming locked due to the occupancy of the switch section by the train in that case before the approach locking can be released.

One object of our invention is to provide means for shortening the time interval imposed upon the release of the locking when the signal which is manually put to stop is a slow-speed signal, in which case the speed of the approaching train will be relatively low.

Another object of our invention is to provide a single time measuring device so arranged that either a relatively long or relatively short time element may be imposed, depending upon whether the signal that is restored to stop is for governing high speed or slow speed traffic movements.

We will describe two forms of apparatus embodying our invention, and will then point out the novel features thereof in claims.

Referring to the accompanying drawing, Fig. 1 illustrates one form of apparatus embodying our invention, while Fig. 2 illustrates a modification of a portion thereof arranged for the control of a train-order signal.

Similar reference characters refer to similar parts in both views.

Referring to Fig. 1, the diagram at the top represents a stretch of railway track comprising a switch section $1T$ containing a track switch 1 and an adjacent approach section AT . Each section is provided with the usual closed track circuit including a normally energized track relay as indicated diagrammatically in the drawing, these track relays being designated ATR and $1TR$, respectively.

The movement of traffic into section $1T$ in the normal direction from left to right is governed by a signal $R2$ comprising a high speed arm a which may be cleared to indicate "caution" or "proceed" in accordance with traffic conditions in advance when section $1T$ is unoccupied and switch 1 is normal, and an auxiliary slow speed arm, or "call-on" signal c , which may be cleared to permit a train to enter section $1T$ at low speed when switch 1 is reversed or section $1T$ is oc-

cupied by a preceding train. The movement of traffic into section $1T$ against the normal direction of traffic is governed by the slow speed signal $L2$. A distant signal RD for governing traffic approaching section $1T$ is located a suitable distance in the rear of signal $R2$, and it is to be understood that in accordance with the usual practice signal RD normally indicates "caution", or "proceed, prepared to stop at next signal", and is cleared to indicate "proceed" only when arm a of signal $R2$ has been cleared to indicate "caution" or "proceed".

The arms a and c of signal $R2$ are controlled by signal relays $RA2H$ and $RC2H$, respectively, and signal $L2$ is controlled by a signal relay $L2H$. The local signal control circuits are not shown in detail, but it is to be understood that each signal arm will be cleared when the corresponding signal relay is energized, and will indicate stop when its signal relay is deenergized. Relays $RA2H$ and $RC2H$ are selectively controlled, through the medium of a lever repeating relay $R2VR$ and an auxiliary relay $C2VS$, by a manually operable signal lever $R2V$, which as shown in the drawing is in its normal position n to which it is moved to cause signal $R2$ to indicate stop. Lever $R2V$ has three positions and may be moved to position r to clear arm a or to position l to clear arm c of signal $R2$.

Switch 1 is actuated by a power operated switch machine ISM controlled in the usual manner, as indicated diagrammatically in the drawing, by a polarized switch control relay $1WR$, which in turn is controlled, when traffic conditions are favorable for the operation of the switch, by the contacts of a switch lever $1V$ in such a manner that switch 1 will be moved to its normal position as shown in the drawing when lever $1V$ is moved to position n and will be reversed when the lever is moved to position r .

Switch machine ISM is provided with the usual indication circuit controller for controlling indication relays $1NKR$ and $1RKR$ as indicated in the drawing, relay $1NKR$ being energized only when switch 1 is closed and locked normal, while relay $1RKR$ is energized only when the switch is closed and locked reverse.

Associated with signal $R2$ there is an approach locking stick relay RMR which becomes deenergized to lock the switch by opening a contact in the circuit for relay $1WR$ when either arm a or c of signal $R2$ is cleared. When signal $R2$ is put to stop, relay RMR may be energized over a pickup circuit which has a plurality of branches, one of which includes a back contact 3 of track relay 55

!TR closed when signal R2 is put to stop automatically by a train passing the signal and entering section !T. Another branch includes a front contact 4 of relay ATR closed when approach section AT is unoccupied, while other branches include contacts of a time-element device TE and of a slow-acting relay TEP, associated therewith.

The time element device TE may be of any suitable type, but as herein illustrated is to be understood as being of the clockwork type as disclosed in the Neubert & McClelland Patent No. 992,236, issued May 16, 1911, but arranged as shown in the Manrodt Patent No. 1,916,485, issued July 4, 1933, to have a contact 5 closed when the control knob is reversed manually to wind up the spring motor, and two other contacts 6 and 7 closed after the knob is released and the clockwork mechanism has been driven by the spring motor for different predetermined times during the return of the contacts to their normal position.

In order to simplify the drawing, we have shown relay contacts which in some instances are not adjacent the respective relays which operate them, but in each case such contacts bear the reference characters identifying the respective relay as well as a number identifying the contact. Thus the branch of the pickup circuit for relay RMR which includes contact 6 of the time element device TE includes a front contact 8 of relay C2VS, which relay controls arm c of signal R2 and remains energized after arm c has been restored to the stop position. As indicated in the drawing, contact 6 closes at the end of a relatively short time period which begins when device TE is released after it has been reversed to close contact 5 to pick up relay TEP, while contact 7, on the other hand, closes when device TE is fully released at the end of a relatively long time period.

The signal relay L2H for signal L2 is controlled by a lever repeating relay L2VR, and this signal has an approach locking relay LMR which corresponds in function to relay RMR for signal R2, but the circuits for relays L2VR and LMR have been omitted in order to simplify the drawing. We have also in the accompanying drawing not shown the source of current for energizing the various relays but have shown in lieu thereof only the terminals of the source which we have identified by the references B and C to designate the supply and common return terminals of the source, respectively.

Assuming the apparatus to be in its normal condition as shown in the drawing, a circuit may be traced from terminal B, contact 10, (closed when signal RD indicates caution or stop), back contact 11 of signal relay RC2H, back contact 12 of signal relay RA2H, front contact 4 of track relay ATR, relay RMR to the other terminal C of the source of current. Relay RMR becomes energized over the circuit just traced and then closes its stick contact 13 bridging contact 4, so that relay RMR will remain energized as long as signal R2 remains at stop.

To clear arm a of signal R2 for an approaching high speed train, the operator moves lever R2V to the *r* position, closing a circuit which may be traced from terminal B, lever contact 14, relay R2VR to terminal C. Since switch 1 is normal, its normal indication circuit which may be traced from terminal B, contact 15 of the circuit controller controlled by switch machine !SM, relay !NKR to terminal C, is closed,

so that relay !NKR is energized. Assuming that signal L2 is at stop, its approach locking relay LMR is energized and the circuit for relay RA2H is closed, which circuit may be traced from terminal B, contact 16 of relay LMR, back contact 17 of relay L2VR, front contact 18 of relay !NKR, front contact 19 of relay R2VR, back contact 20 of relay C2VS, front contacts 21 and 22 of relays !TR and !NKR, relay RA2H to terminal C. Relay RA2H thus becomes energized to clear arm a of signal R2 and opens its back contact 12 to deenergize relay RMR, which relay upon releasing, opens contact 23 in the control circuit of relay !WR to lock switch 1 against operation.

When the approaching train passes signal R2, relay !TR releases, opening contact 21 to deenergize relay RA2H to put the signal to stop and to close its back contact 12 in the pickup circuit of relay RMR, which circuit is completed over back contact 3 of relay !TR so that relay RMR becomes energized. The switch, however, remains locked because contact 24 of relay !TR in the circuit for relay !WR is now open. When the train leaves section !T, relay !TR again picks up, closing the control circuit for relay !WR which may be traced from terminal B, contacts 25, 24, 23 and 26, relay !WR, contact 27 to terminal C. Contacts 25 and 27 constitute a manually operable pole-changer whereby relay !WR may be energized in a direction corresponding to the position of lever !V to control the circuits for switch machine !SM as indicated in the drawing.

Assume now that switch 1 is reversed so that relay !RKR is energized over contact 15, the operator may clear arm c of signal R2 to permit a slow speed train movement over the switch by moving lever R2V to position *l* to close a circuit which may be traced from terminal B, contact 28 of lever R2V, front contact 29 of relay RMR, relay C2VS to terminal C. Relay C2VS then becomes energized, and since contact 14 is also closed in position *l* of lever R2V, relay R2VR becomes energized, and a circuit is closed which may be traced from terminal B, front contact 30 of relay !RKR, front contacts 19 and 20 of relays R2VR and C2VS, relay RC2H to terminal C. Relay RC2H therefore becomes energized to clear arm c of signal R2 and opens contact 11 to release relay RMR to lock the switch. Relay C2VS, however, is a stick relay and will remain picked up, being now energized over its stick circuit which may be traced from terminal B, front contact 31 of relay C2VS, contact 32 of lever R2V, back contact 29 of relay RMR, relay C2VS to terminal C. Relay RC2H is controlled independently of track relay !TR so that arm c will not go to stop when the approaching train enters section !T and therefore to release the locking automatically in this instance, lever R2V must be restored to its normal position *n* to release relays R2VR and RC2H while section !T is occupied.

Assume now that arm a of signal R2 has been cleared but that it is restored to the stop position by returning lever R2V to position *n* when a train is approaching and is occupying section AT. Relays R2VR and RA2H will then release but relay RMR does not pick up because contact 4 in its pick-up circuit is open, due to the presence of the approaching train. To release the locking, the operator reverses the time element device TE, closing contact 5 to complete a circuit which may be traced from terminal B, contacts 75

10, 11 and 12, back contact 13, contact 5, relay TEP to terminal C. Relay TEP picks up and closes its stick contact 33, and remains energized after contact 5 opens. At the end of a predetermined time interval, contact 7 of the time element device TE closes, completing the pickup circuit for relay RMR which includes that contact and front contact 9 of relay TEP, and then relay RMR picks up to complete its stick circuit, 10 and opens back contact 13 to release relay TEP.

Assume next that arm c of signal R2 has been cleared instead of arm a, and arm c is then put to stop by moving lever R2V to position n when a train is approaching and relay ATR is de- 15 energized. To release the locking, the operator is required to operate the time element device TE to pick up relay TEP as before, but in this instance since relay C2VS is picked up, relay RMR becomes energized over the pickup circuit 20 including contacts 8, 6 and 9 at the end of the relatively short time interval when contact 6 closes. Contact 8 of relay C2VS thus serves as a selector contact and causes the short time element measured by the device TE to be effective to 25 release the locking in lieu of the long time element, in the event the signal is manually put to stop and the operation of the device TE is initiated when relay C2VS is energized.

Assume now that arm c of signal R2 has been 30 cleared while switch 1 is normal, and that traffic conditions become more favorable so that the operator desires to clear arm a. To do this, he will move lever R2V from position l to position r. Relay R2VR remains energized, but contact 32 in 35 the stick circuit for relay C2VS opens so that this relay releases, and its back contact 20 closes to complete the signal control circuit for clearing arm a, so that relay RA2H picks up. If lever R2V is then returned to position n, the long time 40 element governed by contact 7 of device TE is effective, and not the short time element governed by contact 6, because contact 8 of relay C2VS is open.

Assume next that with arm a of signal R2 at 45 clear, the operator moves lever R2V from position r to position l to clear arm c. Relay RMR being released, its front contact 29 is open and relay C2VS does not pick up. The operator therefore must hold lever R2V in position n long 50 enough to release relays R2VR and RA2H, and to pick up relay RMR, in order to clear arm c when he moves the lever to position l. If a train is approaching in section AT, the lever must therefore be held in position n for the duration of the 55 long time element. It is thus clear that the operator can not defeat the purpose of the time element device by attempting to clear arm c momentarily after he manually restores arm a to stop, in order to take advantage of the short 60 time interval imposed under certain traffic conditions when arm c is put to stop. After arm c has been cleared, of course, the short time element will be effective upon returning arm c to stop. On the other hand, our apparatus functions in 65 such a manner that the usual "progressive" control of the signals is retained, so that the operator may first clear arm c and then clear arm a without incurring a delay. Arm a, however, will clear only as the result of relay C2VS becoming re- 70 leased, so that the usual long time element will be effective when arm a is restored to stop.

It will be clear from the foregoing that these desirable results are secured by a very simple arrangement of circuits, involving an auxiliary stick 75 relay C2VS for controlling the low speed signal

which relay has a stick circuit arranged to hold the relay energized after the signal is restored to stop, and a pickup circuit controlled by the usual approach locking relay. Furthermore, since the apparatus of our invention may be applied without added complication to a signal governing the movement of traffic over a plurality of switches, it is clear that it may advantageously be employed in large interlockings involving complicated track layouts. In such layouts it is often 10 desirable to provide time locking of the opposing signals. This feature is also provided by our apparatus. Thus, the circuits for relays RA2H and RC2H already traced include in part a portion of a similar circuit for the opposing signal 15 relay L2H, which circuit may be traced from terminal B, back contact 34 of relay C2VS, front contact 35 of relay RMR, back contact 19 of relay R2VR, front contacts 18 and 17 of relays 1NKR and L2VR, relay L2H to terminal C. It 20 follows, therefore, that signal L2 can be cleared only when lever R2V is in position n, signal R2 indicates stop, relay RMR is energized and relay C2VS is deenergized, and that the conditions under which the relatively long or short time element will become effective upon the restoring of signal R2 to its stop position to temporarily prevent operation of the switch, as imposed by the apparatus of our invention, are also effective to 25 prevent clearing of the opposing signal L2. 30

The time element delay imposed upon the clearing of the slow-speed signal after the high speed signal is put to stop, as provided by our apparatus as hereinbefore described, although desirable as a matter of general practice, in some instances may be undesirable, as for example, when arm c of signal R2 is employed as a train-order signal. 35

An arrangement of apparatus by which the effect of the time delay in question upon the signal 40 may be avoided when it is desired to do so is illustrated in Fig. 2. This view shows a portion of the circuits of the signal relays of Fig. 1, which differ from the corresponding parts of Fig. 1 in that the circuit for signal relay RA2H includes an 45 additional contact 36 of lever R2V closed in position r, while to the circuit for signal relay RC2H has been added a by-pass around front contact 20 of relay C2VS, comprising a contact 37 of lever R2V closed in position l and in series therewith a 50 back contact 38 of relay RMR.

Assuming now that the modification shown in Fig. 2 is employed, and that with arm a of signal R2 at clear, the operator moves lever R2V from position r to position l. The circuit of relay RA2H becomes opened at contact 36 of lever R2V and the circuit of relay RC2H becomes closed over contact 37 of lever R2V and back contact 28 of relay RMR so that arm a will go to stop and arm c will clear at once. Relays RMR and C2VS 55 remain deenergized, so that although in this instance the long time element will be effective if arm c is restored to stop when a train is approaching, the operator will be unable to defeat the purpose of the time element. 60

Although we have herein shown and described but two forms of railway traffic controlling apparatus embodying our invention, it is understood that various changes and modifications may be made therein within the scope of the appended 70 claims without departing from the spirit and scope of our invention.

Having thus described our invention, what we claim is:

1. In combination, a stretch of railway track 75

- including a track switch, a signal indicating proceed, slow speed or stop for governing the movement of traffic into said stretch, manually controllable means for governing the signal, locking means effective to prevent operation of the switch for a selected time interval after the signal is manually caused to indicate stop provided there is a train approaching within a predetermined distance of the switch, a stick relay which becomes energized when said manually controllable means is operated to cause the signal to indicate slow speed, and means controlled by said stick relay when energized for shortening said selected time interval.
15. 2. In combination, a stretch of railway track including a track switch, a signal indicating proceed, slow speed, or stop for governing the movement of traffic into said stretch, manually controllable means for governing the signal, a locking relay which when deenergized prevents operation of the switch, means for deenergizing said locking relay when the signal indicates proceed or slow speed and for a selected time interval after the signal is manually caused to indicate stop, provided there is a train approaching within a predetermined distance of the switch, and means causing the selected time interval to be relatively long or relatively short depending upon whether the signal indication is manually changed from proceed to stop or from slow speed to stop.
3. In combination, a stretch of railway track, a signal indicating proceed, slow speed or stop for governing the movement of traffic over the stretch, manually controllable means for governing the signal, a locking relay, means for deenergizing said locking relay when the signal indicates proceed or slow speed and also retaining said locking relay deenergized for a selected time interval after the signal is manually caused to indicate stop provided there is a train approaching within a predetermined distance of the signal, and means controlled by said locking relay effective when said manually controllable means is operated to change the indication of the signal from proceed to slow speed to cause the signal to indicate stop instead of slow speed until said locking relay becomes energized.
4. In combination with a railway track switch, a main signal and an auxiliary signal for governing the movement of traffic over the switch, a signal lever effective when moved from its normal position to a second position to close a contact for clearing the main signal and when moved from its normal position to a third position to close a contact for clearing the auxiliary signal, locking means effective when deenergized to prevent operation of the switch, means for energizing said locking means effective only when both signals indicate stop, a time element device controlled by the signals for delaying the energization of said locking means for a selected time interval after the lever has been restored to normal to put the auxiliary signal at stop and for a longer time interval after the lever has been restored to normal to put the main signal at stop, and means for rendering said time element device ineffective to delay the energization of the locking means when there is no train approaching within a predetermined distance of the signal.
5. In combination with a railway track switch, a main signal and an auxiliary signal for governing the movement of traffic over the switch, a signal lever effective when moved from its normal position to a second position to close a contact for clearing the main signal and when moved

from its normal position to a third position to close a contact for clearing the auxiliary signal, locking means effective when deenergized to prevent operation of the switch, means for energizing said locking means effective only when both signals indicate stop, a time element device controlled by the signals for delaying the energization of said locking means after the lever is restored to normal for a relatively long or relatively short time interval depending on whether the main signal or the auxiliary signal is put to stop by the operation of said lever, and means for rendering the time element device ineffective to delay the energization of said locking means provided there is no train approaching the signal.

6. In combination, a stretch of railway track, a main signal and an auxiliary signal for governing the movement of traffic into said stretch, a locking relay, means for deenergizing the locking relay when either signal is cleared and for a predetermined time after signal is manually caused to indicate stop, manually operable signal control means, a signal control relay, a circuit for the signal control relay closed when said signal control means is operated to clear either signal, a stick relay, a pickup circuit for the stick relay closed when the signal control means is operated to clear the auxiliary signal provided the locking relay is energized, a stick circuit for the stick relay effective to maintain it energized when the locking relay releases, and circuits for selectively clearing the auxiliary signal or the main signal including front contacts of the signal control relay and front and back contacts respectively of said stick relay.

7. In combination, a stretch of railway track including a track switch, a main signal and an auxiliary signal for governing the movement of traffic into the stretch, a three-position signal lever, a signal relay and a stick relay for governing the signals, a locking relay which when deenergized prevents operation of the switch, a circuit for the signal relay closed when the lever is moved from normal to its second or third position, a pickup circuit for the stick relay including a front contact of the locking relay and closed when the lever is in its third position, a stick circuit for the stick relay including its own front contact and also including a back contact of the locking relay and contacts closed when the lever is normal or in its third position, circuits for clearing the auxiliary signal or the main signal including front contacts of the signal relay and front and back contacts respectively of said stick relay, and a circuit for controlling the locking relay when the lever is restored to normal including a front contact of said stick relay.

8. In combination, a stretch of railway track including a track switch, a main signal and an auxiliary signal for governing the movement of traffic into the stretch, a locking relay which when deenergized prevents operation of the switch, means for deenergizing said locking relay when either signal is cleared and for a selected time interval after the signal is manually caused to indicate stop under certain traffic conditions, manually operable signal control means, an auxiliary relay, a circuit for energizing said auxiliary relay controlled by said signal control means and by said locking relay, circuits closed selectively when the signal control means is operated to clear the auxiliary signal or the main signal according as the auxiliary relay is energized or deenergized, and means causing said selected time interval to be relatively short or long depending

upon whether or not the auxiliary relay has been energized.

9. In an interlocking system for railroads, a track switch, two signals for governing the movement of traffic over the switch, locking means rendered effective when either of said signals is cleared to prevent operation of the switch, a time measuring device for releasing said locking means under certain traffic conditions at the end of a measured time interval when a signal is manually put to stop, a selector contact which occupies one position when one signal is put to stop and another position when the other signal is put to stop, and means causing said time interval to be relatively long or relatively short, depending upon the position of said selector contact.

10. In an interlocking system for railroads, a track switch, a high speed signal and a slow speed signal for governing the movement of traffic over the switch, manual control means for the signals, switch locking means rendered effective when either signal is cleared to prevent operation of the switch, a time measuring device for releasing said locking means under certain traffic conditions at the end of a measured time interval after a signal is manually put to stop, and a selector contact controlled by the manual control means for causing said time interval to be relatively long when the high speed signal is put to stop and to be relatively short when the slow speed signal is put to stop.

11. In combination, a stretch of railway track including a track switch, a signal indicating movement, slow speed or stop for governing the movement of traffic into said stretch, manual control means for said signal, locking means effective to prevent operation of the switch under certain traffic conditions for a selected time interval after the signal is manually caused to indicate stop, a selecting relay controlled by the manual control means and by said locking means, means effective when said selecting relay is energized for causing the signal to indicate slow speed when the manual control means is operated to clear the signal, and means effective if said selecting relay is energized for shortening said time interval when the manual control means is operated to cause the signal to indicate stop.

50 12. In an interlocking system for railroads, a track switch, a high speed signal and a slow speed signal for governing the movement of traffic over the switch, manual control means for the signals, a switch locking relay deenergized when either signal is cleared and effective when deenergized to prevent operation of the switch, a slow acting relay, a circuit for the slow acting relay closed only when the signals indicate stop, said circuit including a back contact of the locking relay, time element means effective to pick up said locking relay at the end of a measured time interval after the slow acting relay has become energized, and a selector contact controlled by the manual control means for causing said time interval to be relatively long when the high speed signal is put to stop and to be relatively short when the slow speed signal is put to stop.

65 13. In combination, a stretch of railway track including a track switch, a main signal and an auxiliary signal for governing the movement of traffic into said stretch, a signal lever having a normal, a second and a third position, a locking relay which when deenergized prevents operation of the switch, a stick relay, a pick-up circuit for said stick relay including a front contact of the

locking relay and closed when the lever is in its third position, a stick circuit for said stick relay including its own front contact and also including a back contact of the locking relay and contacts closed when the lever is in its normal position 5 or in its third position, a circuit for clearing the auxiliary signal closed when the lever is in its third position provided either said stick relay is energized or the locking relay is deenergized, a circuit for clearing the main signal closed when the lever is in its second position, and a circuit for controlling the locking relay when the lever is restored to normal including a front contact of said stick relay.

14. In combination, a stretch of railway track 15 including a track switch, a main signal and an auxiliary signal for governing the movement of traffic into said stretch, a locking relay which when deenergized prevents operation of the switch, means for deenergizing said locking relay when either signal is cleared and also retaining said locking relay deenergized for a selected time interval after the signal is manually caused to indicate stop under certain traffic conditions, manually operable signal control means, 20 an auxiliary relay, a circuit for energizing said auxiliary relay controlled by said signal control means and by said locking relay, circuits closed selectively when said signal control means is operated to clear said auxiliary signal or said main 25 signal, and means causing said time interval to be relatively long or short depending upon whether or not said auxiliary relay has been energized.

15. In combination, a stretch of railway track 35 including a track switch, two signals for governing the movement of traffic into said stretch, a three-position signal lever effective when moved to a first position to clear one signal and when moved to a second position to clear the other 40 signal, said lever being effective when in its third position to cause both said signals to indicate stop, locking means effective to prevent operation of the switch for a measured time interval after either signal is caused to indicate stop 45 by the operation of said lever provided there is a train approaching within a predetermined distance of the switch, and means controlled by said lever for governing the length of said measured time interval.

50 16. In combination, a stretch of railway track including a track switch, two signals for governing the movement of traffic into said stretch, a three-position signal lever effective when moved to a first position to clear one signal and when 55 moved to a second position to clear the other signal, said lever being effective when in its third position to cause both said signals to indicate stop, locking means effective to prevent operation of the switch for a measured time interval after either signal is caused to indicate stop by the operation of said lever to its third position provided there is a train approaching within a predetermined distance of the switch, and means dependent upon whether said lever has been moved to 60 said third position from its first position or from its second position for governing the length of said measured time interval.

65 17. In combination with a railway track switch, a plurality of manually controllable signals including a slow speed signal for governing the movement of traffic over the switch, locking means effective when any of said signals is manually put to stop for preventing the operation of said switch for a measured time interval, and 70 75

means effective when said slow speed signal is manually put to stop for shortening said measured time interval.

18. In combination, a stretch of railway track including a track switch, a main signal and an auxiliary signal for governing the movement of traffic over said switch, manually controllable means for governing said signals, locking means for at times preventing the operation of said switch for a measured time interval when either of said signals is manually put to stop, means controlled by said manually controllable means and by traffic conditions in said stretch for clearing said main signal, and means controlled by said manually controllable means and said locking means for clearing said auxiliary signal.

19. In combination, a stretch of railway track including a track switch, two signals at the same location for governing train movements at different speeds into the stretch, manually controllable means for governing said signals, locking means effective when either signal is manually put to stop for preventing the operation of said switch for a measured time interval, and means controlled by said manually controllable means for selecting the length of said measured time interval in accordance with the speed permitted by the signal last cleared. 5 10
